SEWING MACHINE FRAME STRUCTURE

Paul P. Kessler, Chicago, Ill.

Application February 10, 1936, Serial No. 63,048

6 Claims. (Cl. 112—258)

My invention relates to a sewing machine frame structure.

Among the objects of my invention are the following: to create a sewing machine frame structure having an upper portion so attached to a lower portion as to permit both lateral and vertical movement of the upper portion with relation to the lower portion thus permitting both desired off center stitching and the accommodation of different thicknesses and kinds of materials, and such other objects, advantages and capabilities as will later more fully appear and which are inherently possessed by my invention.

While I have shown in the accompanying drawings a preferred embodiment of my invention yet I wish it understood that the same is susceptible of modification and change without departing from the spirit of my invention.

Figure 1 is a side elevation of the sewing machine embodying the several features of my invention.

Figure 2 is a front elevation of the same.

Figure 3 is a rear elevation of the same.

Referring more particularly to the embodiment selected to illustrate my invention, it comprises a frame 10 of two parts having a base or lower portion 11, and an upper portion 12, movably attached to said base 11 by a pair of adjustable hinge screws 13. By the use of my adjustable hinge screws 13, I am able to move the upper portion 12 of the frame 10 laterally, either to the left or to the right so that the stitching member 65 is thereby positioned off center for the purpose of stitching in a desired off center manner. Integral and extending from the rear of the upper portion 12 of the frame 10 is an extension 14, having a hole 15, for receiving a bolt 17. A member 16 preferably extends through an open portion of the lower portion 11 and contacts lever 19 which is fulcrumed on shaft 18. Adjacent its upper end member 16 has a slot 71 slidably receiving bolt 17. Prior to adjustment, bolt 17 is loosened so that member 16 may be moved so that bolt 17 is in the desired position within slot 71. When the bolt 17 is tightened, member 16 is positioned to correctly allow the desired lifting clearance of the upper portion 12 as it is lifted vertically and arcuately to accommodate the desired thickness of material. Bolt 17 may be loosened whenever desired and member 16 moved so that bolt 17 is located in a different position within slot 71 and then tightened for permitting a different desired lifting clearance. The lifting operation is effected through lever 19 which is fulcrumed on shaft 18 and has one

arm normally in engagement with member 16 to impart movement to member 16 upon pressure being applied to lever 19. Of course the adjustment through members 14 and 16 is to provide lifting clearance during the sewing operation independently of the lifting by lever 19. This insures not only proper clearance but proper pressure on different thicknesses and kinds of materials to the highest degree of accuracy.

The lower portion 11 of the frame 10 houses the feeding mechanism 21 of the construction defined and claimed in my co-pending application, Serial No. 78,051, filed May 5, 1936.

Having thus described my invention I claim:

1. In a sewing machine frame structure, a body member having a lower portion and a separate upper portion, and adjustable means movably attaching said lower and upper portions, said means permitting lateral adjustment of the upper portion for desired off center stitching. 20

2. In a sewing machine frame structure, a body member having a lower portion, and a separate upper portion, and a pair of adjustable hinge screws for movably attaching said lower and upper portions, said hinge screws, permitting lateral adjustment of the upper portion for desired off center stitching. 25

3. In a sewing machine frame structure, a body having a lower portion carrying a feeding mechanism, and an upper portion carrying a stitching mechanism, adjustable means for attaching said upper portion to said lower portion to permit both lateral adjustment of said upper portion with respect to said lower portion for desired off center stitching, and also vertical movement of said upper portion with respect to said lower portion to accommodate different thicknesses and kinds of material, said upper portion adapted to act of its own weight as a pressure means during a sewing operation. 40

4. In a sewing machine frame structure, a body having a lower portion carrying a feeding mechanism, and an upper portion carrying a stitching mechanism, adjustable means for attaching said upper portion to said lower portion to permit both lateral adjustment of said upper portion with respect to said lower portion for desired off center stitching, and also vertical movement of said upper portion with respect to said lower portion to accommodate different thicknesses and kinds of material, said upper portion adapted to act of its own weight as a pressure means during a sewing operation, adjustable means attached to said upper portion for controlling the desired lifting clearances of the upper portion with re- 55

spect to the lower portion and manually operable means for lifting said upper portion.

5. In a sewing machine frame structure a lower portion, an upper portion, means for movably attaching the upper portion to the lower portion, said upper portion having an extension, said extension having a bolt, a member having a slot, said bolt slideable within said slot and adapted to be tightened at any desired position within 10 said slot so as to permit desired lifting clearances of the upper portion with respect to the lower portion for accommodating different thicknesses of material and manually operable means engageable with said member for lifting said upper 15 portion.

6. In a sewing machine frame structure, a body member having a stationary lower portion carrying a feeding mechanism and a separate upper portion carrying a stitching mechanism, a hinge for attaching the upper portion to the lower portion to permit vertical movement of the upper portion and the stitching mechanism it carries with respect to the lower portion and its feeding mechanism, said upper portion adapted to act of its own weight as a pressure means 10 so that during the sewing operation the stitching mechanism will automatically adjust itself to apply the proper pressure on different thicknesses and kinds of material. 5
